PERFORATION CLEANING DEVICE

Carl J. McCoy, Orcutt, Calif.

Application May 24, 1948, Serial No. 28,786

7 Claims. (Cl. 166—18)

1

This invention relates to a device for cleaning perforations in a casing of the type employed in wells and is particularly directed to apparatus for continuously cleaning the casing perforations during the operation of the well pump for pumping fluid from the well. This device finds particular usefulness in connection with the production of petroleum from oil wells.

This application is a continuation in part of my copending application for "Brush for Well Casings," Serial No. 651,449, filed March 2, 1946, now abandoned.

The principal object of this invention is to provide a device for automatically cleaning casing perforations during operation of the pump for raising fluid from the well, the device being caused to travel vertically in the well by reason of the relative movement between the tubing and casing occasioned by operation of the pump at the lower end of the tubing.

Another object is to provide a cleaner device of this type which travels upwardly along the tubing for a predetermined distance and then reverses its direction of travel automatically during normal operation of the well pump.

Another object is to provide a cleaner device having its spring fingers movable into and out of casing perforations which are yieldable to permit movement of the cleaner device in either direction within the casing.

Another object is to provide mechanism for automatically moving a cleaner device within perforated casing in a step by step manner in accordance with relative movement between the tubing and casing occasioned by operation of the well pump.

A more particular object is to provide a novel form of releasable clutch construction which is operable to propel the cleaner device in either direction.

Another object is to provide a novel form of mounting for the spring fingers which are adapted to engage within the perforated slots in the casing.

Other objects and advantages will appear hereinafter.

In the drawings:

Figure 1 is a sectional side elevation partly broken away showing a preferred embodiment of my invention positioned within a well bore.

Figure 2 is a side elevation partly in section on an enlarged scale illustrating details of construction of a cleaner device embodying my invention.

Figure 3 is an elevation view partly broken 55 foot valve 20 remains closed. The alternate in-

2

away taken in the direction of the lines 3—3 as shown in Figure 2.

Figure 4 is a sectional plan view taken substantially on the lines 4—4 as shown in Figure 2.

Figure 5 is a sectional plan view taken substantially on the lines 5—5 as shown in Figure 2.

Figure 6 is a sectional detail taken substantially on the lines 6—6 as shown in Figure 1.

Figure 7 is a sectional perspective view illustrating the mounting of the spring fingers on the cleaner device.

Figure 8 is a perspective view partly broken away showing the body of the cleaner device.

Figure 9 is a sectional elevation taken substantially on the lines 9—9 as shown in Figure 3.

Figure 10 is a perspective view of a subassembly including the clutch plate and releasable latching mechanism.

Figure 11 is a view similar to the upper portion 20 of Figure 10 showing the upper latching spring in compressed position.

Figure 12 is a partial sectional plan view taken substantially on the lines 12—12 as shown in Figure 9.

25 Figure 13 is a partial sectional plan view of a portion of the apparatus shown in Figure 4 but with the latching lug rotated to release position.

Referring to the drawings, the casing 10 within the well bore may be provided with the usual 30 perforated slots 11 which are adapted to allow well fluid to enter the casing 10. A well pump generally designated 12 and shown diagrammatically in Figure 1 may be positioned within the lower end of the tubing 13 which extends downwardly within the bore hole from the surface. The tubing 13 constitutes an eduction conduit for well fluid and is made up of sections connected by threaded collars 14. A jointed sucker rod 15 extends downwardly within the tubing 13 and is connected at 16 to reciprocate the pump plunger 17 within the pump barrel 18.

The usual traveling valve 19 is provided on the plunger 17, and the standing valve 20 is mounted at the lower end of the barrel 18. The 45 pump 12 may take any suitable or conventional form and is shown diagrammatically for illustrative purposes only. The sucker rod 15 is reciprocated at the surface by means of a suitable pumping jack (not shown). When the sucker rod 15 moves upwardly, the weight of the well fluid in the tubing 13 is carried on the pump plunger 17. When the sucker rod 15 moves downwardly, however, the weight of the well fluid within the tubing 13 is carried by the tubing 13, since the 50 55 foot valve 20 remains closed. The alternate in-

crease and decrease of weight occasioned by actuation of the pump 12 causes the tubing length to lengthen and contract in accordance with the operating strokes of the pump plunger 17. Since the tubing may be several thousand feet in length, the relative movement between the tubing 13 and casing 12 near the lower end of the tubing may amount to several inches or more for each stroke of the pump.

In accordance with my invention I make use of the alternate stretch and contraction of the tubing relative to the casing for moving a perforation cleaner vertically within the casing 10. The perforation cleaner device is generally designated 21 and is adapted to travel on the tubing 13 between spaced coupling collars 14. Although only one perforation cleaner device is shown and described, it will be understood that additional devices 21 may be installed on the tubing between each pair of coupling collars 14 throughout the length of the perforated casing 10. It will be understood by those skilled in the art that the perforated casing 10 is carried at the lower end of imperforate casing extending from the well surface.

The cleaner device 21 comprises a body 22 having a pair of vertically spaced end flanges 23 extending by vertically extending bars 24, 25 and 26. A tubular guide 27 projects from each of the end flanges 23 and is provided with threads 28 at its projecting end. Each of the tubular guides 27 is provided with a longitudinal slot 29. The tubular guides 27 are adapted to encircle the tubing 13 for sliding movement thereon. Upper and lower brush assemblies generally designated 30 and 31 are adapted to be mounted on the tubular guides 27. Each of these brush assemblies includes a nut 32 having internal threads 33 adapted to engage the threads 28 on the outer end of the tubular guides 27. An adapter 34 rests against each of the end flanges 23 and is provided with an annular shoulder 35 adapted to receive one end of the spacer 36. The upper end of the spacer 36 is received against a similar shoulder 37 provided on the nut 32. From the above description it will be understood that the spacer 36 is clamped between the annular shoulders 35 and 37. A plurality of slots 38 are formed in the spacer 36, adapter 34 and nut 32, as shown clearly in Figure 7. A plurality of spring elements 39 are mounted on the spacer 36, and each is provided with a pair of vertically spaced prongs 40 projecting radially outwardly through the slots 38. The spring elements 39 each may be formed from a single length of spring wire having a loop 41 at the inner end of each of the projections 40 and a central loop 42 which projects outwardly through an aperture 43 provided in the spacer 36. A retainer wire 44 extends circumferentially around the spacer 36 and through the central loops 42 to prevent displacement of the spring elements 39. Adjacent spring elements 39 may have their central loops 42 positioned at different elevations in order that the apertures 43 may be positioned in two parallel rows and thus avoid undesirable weakening of the spacer 36 which would occur if all of the apertures 43 were located in a single row. Accordingly, a second retainer wire 45 may be employed to secure alternate spring elements 39 in position on the spacer 36.

The opposite ends of the clearance slots 38 may be cut on an angle as shown at 46 in order to limit the extent of the angular movement of the projections 40. Movement of the cleaner device

21 vertically within the perforated casing 10 causes the projections 40 to extend into the perforations 11 and thereby free the perforations of sand, grit or other foreign matter, thus permitting entrance of well fluid into the casing 10. As shown in Figure 6, the projections 40 engage the inner wall of the casing 10 until such time as movement of the cleaner device 21 brings the projection opposite one of the elongated slits or perforations 11. The projection 40 then moves into the perforation 11 and is carried upwardly with the cleaner device 21. The position of the projection 40 when operating within the perforation is shown by the dotted lines 40a in Figure 6. As the cleaner device 21 continues to move relative to the casing 10, the projection 40 strikes the end of the elongated slit or perforation and is then bent back into position to engage the inner wall of the casing 10.

20 Means are provided for moving the body 22 and brush assemblies 30 and 31 along the tubing 13 between adjacent end collars 14. As shown in the drawings, this means includes a releasable clutch plate 47 having a central opening 48 through which the tubing 13 extends. The opening 48 is shaped so that it grips the surface of the tubing 13 when the plate 47 is tilted to a sufficient angle with respect thereto. The plate 47 is provided with a projecting portion 49 adapted to be received within a horizontal slot 50 provided in the bar 24 on the body 22. On the opposite side of the clutch plate 47 from the projection 49 is an ear 51 provided with an opening 52. The ear 51 is adapted to extend into a central opening 53 provided in clutch control element 54. This clutch control element is mounted between a pair of axially aligned oppositely extending vertical tubes 55 which are integrally connected to the element 54 and are adapted for sliding movement relative to a pair of axially aligned guide pins 56 carried on the end flanges 23.

The assembly including the tubes 55 and the clutch control element 54 is hereinafter generally designated the control member 57. Flanges 58 and 59 are provided at opposite ends of the control member 57 and adapted to engage the end flanges 23 on the body 22. A pair of gripper springs 60 and 61 are mounted on the control member 57 within the clutch control element 54. A pair of cross pins 62 extending through the tubes 55 contact one end of each of the springs, and the other end of each spring engages the ear 51 on the clutch plate 47. If desired, the wire at one end of each of the coil springs 60 and 61 may be projected through the aperture 52 in the ear 51 in order to prevent disassembly of the ear from its position between the gripper springs. The construction just described provides a floating mounting for the ear 51 between the opposed compression coil springs 60 and 61.

A pair of shifter springs 63 and 64 encircle the tubes 55, and each contacts a shoulder 65 and 66 provided on the clutch control element 54. The upper end of the coil spring 63 rests against a shoe 67 encircling the upper tube 55, and the lower end of the spring 64 contacts a similar shoe 68 encircling the lower tube 55. The shoe 67 carries an upwardly extending trip finger 69 and the lower shoe 68 carries a downwardly extending trip finger 70. The fingers 69 and 70 extend through slots 29 provided on the body guides 27 and project outwardly beyond the position of the nuts 32.

A downwardly projecting lug 71 is provided on the shoe 67 and a similar upwardly projecting lug 72 is provided on the shoe 68. Each of these lugs is provided with a bevelled surface 73 and 74 respectively. An upwardly directed cooperating lug 75 is formed integrally on the clutch control element 54 and is provided with a bevelled surface 76. Similarly, a downwardly projecting lug 77 also is formed integrally on the clutch control element 54 and provided with a bevelled surface 78. Compression of the spring 63 from the position shown in Figure 10 to the position shown in Figure 11 serves to bring the cooperating bevelled surfaces 73 and 76 into engagement, thereby rotating the clutch control element 54 in a clockwise direction as viewed in Figure 13. In similar fashion, compression of the lower shifter spring 64 serves to bring the bevelled surfaces 78 and 74 into engagement, and this action also rotates the clutch control element 54 in a clockwise direction as viewed in Figure 13.

A latching lug 79 provided on the clutch control element 54 is adapted to enter either one of a pair of recesses 80 and 81 provided on the vertical bar 25. When the latching lug 79 on the clutch control element 54 is engaged with the upper recess or notch 80, the clutch plate 47 assumes the position shown in Figures 2 and 9 with the ear 51 at a higher elevation than the horizontal slot 50. When the latching lug 79 is positioned in engagement with the lower notch 81, the clutch plate 47 assumes the dotted line position 47a, as shown in Figure 2. In operation the cleaner device generally designated 21 is installed on one or more sections of tubing 13 between coupling collars 14 and is run into the well with the tubing string so as to position the cleaner adjacent the perforated casing 10. The tubing carries the pump 12 at its lower end.

Reciprocation of the sucker rod 15 from the surface serves to reciprocate the pump barrel 17 and to cause well fluid to be pumped upwardly through the tubing 13 to the surface. As the tubing alternately lengthens and shortens due to the action of the pump 12 as set forth hereinabove, the lower end of the tubing 13 reciprocates within the relatively stationary casing 10. The projections 40 of the spring elements 39 engage within the inner wall of the casing and extend into the perforations 11. Assuming that the clutch plate 47 is in the full line position shown in the drawings, downward movement of the tubing 13 relative to the perforated casing 10 releases the gripping action of the plate 47 on the surface of the tubing 13 and allows the tubing to descend. The cleaner device 21 remains in place and does not descend with the tubing, because the projections 40 offer sufficient frictional resistance within the casing 10 to overcome the action of gravity.

When the tubing 13 moves upwardly the clutch plate 47 grips the surface of the tubing 13 and the entire cleaning device 21, including the body 22 and brush assemblies 30 and 31, is carried upwardly for substantially the full amount of upward movement of the tubing 13. Downward movement of the tubing 13 again releases the gripping action of the plate 47, and the cleaner device 21 remains in place until the next upward movement of the tubing. This action continues with the cleaner device 21 moving upwardly step by step until the upper end of the finger 69 engages under the connecting collar 14. Subsequent upward movement of the cleaner device with the

subsequent downward movement of the tubing 13 causes the finger 69 and its shoe 67 to compress the upper shifter spring 63. This action eventually brings the bevelled surfaces 73 and 76 into engagement, thereby rotating the control member 57 and moving the latching lug 79 out of the upper notch 80 on the vertical bar 25. The energy stored within the compressed coil spring 63 then acts to shift the control member 57 downwardly to bring the flange 59 into engagement with the end flange 23 on the body 22. The latching lug 79 enters the notch 81 in the vertical bar 25.

The upper spring 63 provides torsion to rotate the control member 57 in a counterclockwise direction as viewed in Figure 13 to maintain the latching lug 79 within the lower notch 81. The torsion may be supplied in any desired manner, and as shown I prefer to employ the upper spring 63 for this purpose. The upper end 82 of the wire forming the spring 63 may bear against one side of the shoe 67, and the lower end 83 of the wire may be anchored within a hole 84 provided in the wall of the upper tube 55 adjacent the clutch control element 54.

When the clutch plate 47 assumes the position shown in dotted lines in Figure 2 and designated 47a by reason of engagement of the latch lug 79 with the lower notch 81, the cleaner device 21 begins its movement downwardly within the casing 10. Upward movement of the tubing 13 serves to release the gripping action of the plate 47 on the surface of the tubing 13, permitting it to move upwardly without moving the cleaner device 21. Downward movement of the tubing 13, however, causes the clutch plate 47 to grip the tubing 13 and to move the cleaner device 21 downwardly for substantially the full stroke of the lower end of the tubing. The cleaner device 21 therefore moves downwardly step by step as the lower end of the tubing reciprocates, and this action continues until the finger 70 which extends downwardly below the lower nut 32 engages a lower coupling collar 14 on the tubing. The finger 70 is moved upwardly on the next upward stroke of the tubing and collar 14, and this action serves to raise the shoe 68 to compress the lower shifter spring 64.

Compression of the shifter spring 64 serves to bring together the bevelled surfaces 74 and 78 and thereby rotate the control member 57 in a clockwise direction as viewed in Figure 13 to release the latch lug 79 from the lower notch 81. The energy stored in the lower shifter spring 64 then shifts the control member 57 upwardly, and the torsion action of the upper spring 63 rotates the member 57 to bring the latching lug 79 into engagement with the upper notch 80. The clutch plate 47 reassumes its full line position as shown in Figure 2, and the cleaning device again proceeds upwardly along the tubing 13, thus repeating the cycle.

The gripper springs 60 and 61 for the ear 51 on the clutch plate 47 provide a floating mounting for one end of the clutch plate 47 so that it may move sufficiently to grip and release the pipe 13 in the manner just described. The brush assemblies 30 and 31 by moving continuously between the coupling collars 14 serve to keep the casing perforations free of obstructing material to facilitate flow of well fluid into the casing 10. The spring mounted projections 40 move inwardly about the center loops 42 to permit reversal of movement and thereby cause the projections to be moved to a trailing position. The resilience

of the spring elements 39 plus the spring action obtained by the loops 41 and 42 insures an effective cleaning action without resulting in any permanent deformation of the spring elements 39. The use of my improved cleaner device 21 which operates automatically with the alternate stretch and contraction of the tubing serves to keep the casing perforations clean while the pump 12 is operating. The expense and time required for periodic removal of the pump in order to clean the casing perforations are eliminated with consequent increase in overall production from the well.

Having fully described my invention, it is to be understood that I do not wish to be limited to the details herein set forth, but my invention is of the full scope of the appended claims.

I claim:

1. A device for cleaning perforate well casings comprising in combination: a body axially movable along a string of well tubing through a string of perforated casing sections; a collar secured to the body, said collar having a row of slots spaced around its periphery adjacent an end thereof and an aperture corresponding to each slot; springs mounted within the collar, each spring comprising a main portion having a central loop therein which projects through one of said apertures, and an end portion projecting outwardly through the corresponding slot in the collar for engaging the casing; and a continuous retainer wire member encircling the periphery of said collar and threaded through said central loops, thereby securing said springs to said collar.

2. A device for cleaning casing perforations comprising in combination: a body slidably mountable upon a reciprocable string of well tubing for introduction therewith into a well casing; fingers carried by the body for brushing and frictionally dragging on the interior of the casing to clear obstructions from perforations therein; a clutch member carried by the body and engageable with said tubing, said clutch member being movable between a first position permitting upward movement of said body relative to said tubing but resisting relative downward movement thereof, and a second position wherein the action of said clutch member is reversed; a device connected to the clutch member for moving the clutch member between its first and second positions; stops positioned at predetermined points along the length of the string of tubing; and means carried by the body and movable thereby into engagement with the stops for actuating said device to reverse the clutch.

3. In a well apparatus wherein a well casing is provided with a perforated zone, an eduction tube is suspended in the casing and is provided with a reciprocating pump and wherein on operation of said pump, the region of said eduction tubing in the zone of said perforations is caused to reciprocate relative to the casing due to variation in fluid loads impressed on the tubing, the combination of a well cleaner, comprising: a frame structure adapted to be slidably mounted on said eduction tubing in the region of said perforations; a plurality of perforation cleaning fingers carried by said frame structure and engageable with the walls of said casing and capable of penetrating the openings therein; said fingers providing a yieldable frictional connection between said frame structure and said casing tending to maintain said frame structure fixed relative to said casing; and a clutch means carried by said frame structure adapted to engage said

eduction tubing to secure said frame structure relative thereto during movement of said eduction tubing relative to said casing in one direction, and to disengage said eduction tubing on movement of said tubing relative to said casing in the opposite direction, whereby said frame structure tends to travel along said casing and eduction tubing as said tubing is reciprocated.

4. In a well apparatus wherein a well casing is provided with a perforated zone, an eduction tube is suspended in the casing and is provided with a reciprocating pump and wherein on operation of said pump, the region of said eduction tubing in the zone of said perforations is caused to reciprocate relative to the casing due to variation in fluid loads impressed on the tubing, the combination of a well cleaner, comprising: a frame structure adapted to be slidably mounted on said eduction tubing in the region of said perforations; a plurality of perforation cleaning fingers carried by said frame structure and engageable with the walls of said casing and capable of penetrating the openings therein; said fingers providing a yieldable frictional connection between said frame structure and said casing tending to maintain said frame structure fixed relative to said casing; and a clutch means carried by said frame structure adapted to engage said eduction tubing to secure said frame structure relative thereto during movement of said eduction tubing relative to said casing in one direction, and to disengage said eduction tubing on movement of said tubing relative to said casing in the opposite direction, whereby said frame structure tends to travel along said casing and eduction tubing as said tubing is reciprocated; and means spaced on said eduction tubing for reversing the operation of said clutch means to effect travel of said frame structure back and forth between said spaced means.

5. In a well pumping apparatus having a casing, an eduction tubing in the casing and a reciprocating pump near the lower end of the tubing wherein the eduction tubing is caused, by action of the pump, to reciprocate relative to said casing, the improvement comprising a device for cleaning perforations in the casing including the combination of: a body adapted to be slidably positioned upon a string of eduction tubing for introduction therewith into a well, there being stops on said eduction tubing to limit sliding movement of said body; cleaning fingers carried by the body for cleaning the casing perforations and affording a frictional drag tending to prevent movement of said body relative to said casing and thereby to cause movement thereof relative to said eduction tubing; clutch means carried by the body interengaging said body and eduction tubing during movement of said tubing in one direction relative to said casing to force said body to move with said eduction tubing, and disengaging said body from said tubing during movement of said tubing in the opposite direction whereof said body tends to remain stationary in said casing but move relative to said eduction tubing thereof on repeated reciprocation of said tubing to progress the body along the tubing in cleaning engagement with the casing; and a mechanism carried by said body and engageable with the stops on said eduction tubing for automatically reversing the position of said clutch means so as to interengage said body and eduction tubing when said eduction tubing moves in said opposite direction, and to disengage said body and eduction tubing when said eduction tubing

is moving in said one direction, thereby to cause progression of said body in the opposite direction.

6. A device for cleaning well casing perforations, comprising: a body adapted to be slidably mounted on a reciprocable string of well tubing and lowered therewith into a well casing, there being spaced stops on said well tubing to limit sliding movement of said body on said well tubing; cleaning fingers carried by the body for frictionally engaging and cleaning the casing perforations; a clutch member carried by said body and having a central opening to receive said well tubing, said clutch member being tiltable on said well tubing between a first and second extreme position, whereby in the first position of said clutch member, the margins of said opening tend to grip the well tubing on downward movement of the well tubing relative to the clutch member and to slide on the well tubing on upward movement of the well tubing relative to the clutch member, and whereby in the second position of said clutch member the margins of said opening tend to grip the well tubing on upward movement of the well tubing relative to the clutch member and to slide on the well tubing on downward movement of the well tubing relative to the clutch member; said clutch member thus tending, when in its first position, to advance said body downwardly on said well tubing, and when in its second position, to advance said body upwardly on said well tubing; and a clutch shifting means mounted on said body and cooperating with the stops on said

well tubing to shift said clutch member between its first and second positions, thereby to cause said body member to progress alternately, downwardly and upwardly on said well tubing.

5 7. A device for cleaning casing perforations comprising in combination: a body mountable upon a reciprocable string of well tubing for introduction therewith into a well casing; fingers carried by the body for brushing and frictionally dragging on the interior of the casing to clear obstructions from perforations therein; a tilting clutch member carried by said body and engageable with said tubing, said clutch member being movable between a first position permitting upward movement only of said body member relative to said tubing and a second position permitting downward movement only of said body member relative to said tubing; stops positioned at predetermined points along the length of the 10 string of tubing; and an operating mechanism carried by said body and engageable with said stops to move said clutch member between its 15 first and second positions.
